UNITED STATES PATENT OFFICE.

LLOYD T. MURPHY, OF ST. MARYS, OHIO.

CONTINUOUS EXTRACTOR.

1,414,703.

Specification of Letters Patent. Patented May 2, 1922.

Application filed July 6, 1920. Serial No. 394,113.

To all whom it may concern:

Be it known that I, LLOYD T. MURPHY, a citizen of the United States, and a resident of the city of St. Marys, in the county of 5 Auglaize and State of Ohio, have invented certain new and useful Improvements in Continuous Extractors, of which the following is a full, clear, and exact description, reference being had to the drawings, forming 10 part of this specification.

My invention relates to extractors for removing finished stock from a paper beater, during the beating process in a continuous manner.

15 There are now a number of different forms of continuous extractors in use, among which are (1) the type wherein a revolving foraminated cylinder set into the tub washes out the finely beaten material 20 and (2) the type wherein the stock is flung by centrifugal force from the beater proper, against a screen, which selectively separates the finished from the unfinished stock.

25 My invention lies between these two types, regarding it from one point of view, in view of the fact that I withdraw my stock from the beater by means of centrifugal force, and then separate the fine from the coarse stock 30 in a revolving foraminated cylinder into which the material is fed, and through the meshes of which the finely ground material escapes.

35 One very great advantage which I gain by my method of operation is that I can employ a current or spray of water for cleaning the stock away from the holes in the cylinder, since the difficulty of all machines for the above purpose, of which I have knowledge, is that the coarse stock so 40 clogs the holes in the extractor that it is difficult to keep them clean enough to give any more than a mere partial extraction.

I accomplish the objects of my invention by that certain construction and arrangement of parts to be hereinafter more specifically pointed out and claimed.

In the drawings,

Figure 1 is a top plan view of my machine.

50 Figure 2 is a perspective view of the same. The ordinary beater tub is shown at 1, in which is the beater having a shaft 2 covered by the hood 3. The beater is driven by a belt operating over a pulley wheel 4, 55 or by any other desired means.

The hood opens at the end which will re-

ceive the centrifugally thrown stock from the beater, and at this point is set a box 5, the shape of which is preferably triangular and terminates in a mouth 6. The top 7 of 60 the box has a handle 8 and is preferably removable for purposes of inspection and the like.

The base of the box slopes downwardly so as to carry the material flung from the 65 beater by its centrifugal action to a cylinder 9, having a series of holes therein as at 10, and having preferably heavy rims 11, which extend beyond the face of the cylinder proper. This cylinder is mounted on suitable bearings and rests on a revolving device made up of rollers 13, there being two 70 shafts 14, with a roller at each end of each shaft, which rollers drive the cylinder ends around in a frictional manner.

75 The shafts 14 are equipped with pulleys 15, which are connected by a belt 16 and one of the shafts extends outwardly from the tub, where it is fitted with pulleys 17, for being driven off of a pulley 18 on the 80 main shaft of the beater or any other convenient means.

A sprinkler pipe 19 is mounted over the cylinder and directs sprays of water against the foraminated surface thereof, which acts 85 to clear the holes, and keep them clear of all large material which may adhere therein.

A trough 20 is mounted beneath the cylinder, and opens upwardly so as to receive material falling through the holes of the 90 cylinder. It also extends out at one side of the cylinder to catch the material flung out by centrifugal action therein, if any, and its mouth 21 extends out over the side of the beater tub.

95 Preferably I also provide a revolving shaft 22, at the lower end of the mouth of the box leading from the beater hood which shaft is revolved by means of a belt 23, and pulley 24 and acts to feed into the box the 100 stringy material which might otherwise clog up the orifice between the box and the hood.

As so constructed the mechanism operates 105 as follows:—The material thrown out by centrifugal force by the beater, which is in itself a partially selected stock is caught by the mouth letting into the closed box. The revolving shaft at the base of the mouth into this box maintains the mouth clear.

110 After flowing by gravity through the box the material falls into the interior of the cylinder, which is constantly revolved by

the rollers against which it rests. The spray of water acts to keep the holes constantly clean of large pieces of material. The small material, being able to flow through the 5 holes, will be to a large part caught in the trough member, and thence conducted to the desired point, such as, for example, to a jordan.

The large material will flow out through 10 the open end of the cylinder away from the trough and fall back into the tub to be beaten up.

In this way the tub may be constantly 15 charge with water and unbeaten stock, and the finished stock will be constantly drawn off, so as to make the beating process a continuous one.

I have not attempted to describe in great 20 detail the various parts of my mechanism, and advisedly so, because the essential principle may readily be accomplished with various forms of equivalent mechanisms, which I desire to include within the scope 25 of my invention.

Having thus described my invention, what 30 I claim as new and desire to secure by Letters Patent, is:—

1. In combination with a beater and a tub, 35 a box for catching the material thrown by centrifugal force from the beater, and a revolving cylinder into which the box empties, said cylinder having a foraminated body, for the purpose described.

2. In combination with a beater and a tub 40 35 and a hood over the beater, of a closed box letting into the hood over the beater, and adapted to catch and conduct away material thrown by centrifugal force from the beater, and foraminated means in communication with the box for selectively removing the fine stock from the material and conducting 45 it away from the tub.

3. In combination with a beater and a tub 45 50 and a hood over the beater, of a closed box letting into the hood over the beater, and adapted to catch and conduct away material thrown by centrifugal force from the beater, and foraminated means in communication with the box for selectively removing the fine stock from the material and conducting it away from the tub, said means comprising a cylinder suitably revolved, said cylinder having a trough set to catch the fine material

and open at its end to pour the coarse material back into the tub.

4. In combination with a beater and a tub 55 and a hood over the beater, of a closed box letting into the hood over the beater, and adapted to catch and conduct away material thrown by centrifugal force, from the beater, and foraminated means in communication 60 with the box for selectively removing the fine stock from the material and conducting it away from the tub, said foraminated means having a water spray device for cleaning the holes thereof.

5. In combination with a beater and a tub 65 and a hood over the beater, of a closed box letting into the hood over the beater, and adapted to catch and conduct away material 70 thrown by centrifugal force, from the beater, and foraminated means in communication with the box for selectively removing the fine stock from the material and conducting it away from the tub, comprising a revolving 75 shaft set at the lower end of the said entrance.

6. In combination with a beater and a tub 80 and a hood over the beater, of a closed box letting into the hood over the beater, and adapted to catch and conduct away material thrown by centrifugal force, from the beater, and foraminated means in communication 85 with the box for selectively removing the fine stock from the material and conducting it away from the tub, comprising a revolving shaft set at the lower end of the said entrance.

7. In combination with a beater and a tub 90 and a hood over the beater, of a closed box letting into the hood over the beater, and adapted to catch and conduct away material thrown by centrifugal force from the beater, and foraminated means in communication 95 with the box for selectively removing the fine stock from the material and conducting it away from the tub, said means comprising a cylinder suitably revolved, said cylinder having a trough set to catch the fine material and open at its end to pour the coarse 100 material back into the tub, and having a water pipe extending across it; adapted to send sprays of water thereagainst to clear the foraminated portions thereof.

LLOYD T. MURPHY.
